HIS ATTORNEY.

UNITED STATES PATENT OFFICE

2,130,926

FOUNTAIN PEN

William G. Nichol, Philadelphia, Pa.

Application July 15, 1937, Serial No. 153,812

4 Claims. (Cl. 120—46)

This invention relates to fountain pens and more particularly to the conventional types which are usually filled with the desired writing fluid by the use of an outside instrumentality, in contradistinction to the numerous other varieties which are more or less periodically replenished by manipulation of interassociated filling means.

The primary object of this invention is to provide an improved type of fountain pen including a novel feed structure whereby the barrel of the pen can be substantially filled to its maximum capacity.

Another object is to provide a fountain pen of the indicated character in combination with a novel filler means which is adapted to fill the pen to a greater capacity than heretofore possible and which, when withdrawn, leaves the pen automatically sealed against leakage, while the disadvantage of "sweating" is reduced to the minimum.

With the foregoing and other objects in view which will hereinafter appear, or be specifically referred to, as well as ancillary advantages arising therefrom; this invention consists essentially in the novel features of construction, combination and arrangements of parts and associated items hereinafter disclosed and more concisely expressed in the concluding claims.

In the drawing—

Fig. 1 is a broken view, mainly in longitudinal section of a fountain pen embodying this invention.

Fig. 2 is a view of the associated filler means.

Fig. 3 is a closure pin for the filler of the preceding illustration.

Fig. 4 is an elevation of a protective case or container for the filler, when not in use.

Fig. 5 is a mainly sectional view, illustrative of the manner in which the improved fountain pen of this invention is filled with writing fluid.

Fig. 6 is a perspective view of a clamp ring, hereinafter fully described; and

Fig. 7 is a broken sectional view of a slightly modified form of the invention.

In all the views corresponding parts are designated by like reference numerals except as later on pointed out.

Referring more in detail to the drawing the barrel or ink containing section of the improved fountain pen is comprehensively designated by the numeral 10, the same being internally screw-threaded at its open end 11, for reception of a removable feed-section 12, carrying the "nib" or pen point 13; and 14 similarly indicates generally the closure or cap, which in accordance with the

illustrated form of the invention is of the friction grip type.

In connection with the section 12 the numeral 15 indicates the customary "nib" feeding groove, and it is to be particularly remarked that in accordance with the invention the inner end of said section is suitably reduced at 16 to receive a rubber closure or "nipple" 17 of a length so that when cemented or otherwise fixed in position it provides a hemispherical hollow cap 18. 5 Through the feed 12 there is also drilled or otherwise provided an axial passage 12', of small diameter, for free passage of the tubular needle portion 19 of a filler 20. This filler 20 is preferably of hollow bulbous formation, as shown, with the 10 needle portion 19 of the hypodermic type and having a tapering end 21 adapted to centrally 15 pierce the cap 18 aforesaid.

Now, it will be readily understood that upon inserting the filter needle-portion 19 into a supply of the desired writing fluid and by collapsing the hollow bulbous portion 20, and then releasing the applied pressure, that said bulbous portion will be automatically filled to capacity by suction, and is now ready for filling the pen barrel 20 10, by passing the needle portion 19 through the filler section axial passage 12' until it pierces the nipple 17, in an obvious manner. It will also be observed that when the "filling" pressure is released from the bulbous portion 20, and the latter 20 15 is withdrawn from out of the passage 12', that the barrel contained fluid pressure will also aid in automatically closing the incision made by the needle 19 through the nipple 17. Obviously the needle cross section may be of any desired 25 20 contour than circular if desired to prevent the puncturing of the "nipple" 17 in more than one place, but it has been found by extensive experimentation that the puncturing of said nipple extensively 30 has in no noticeable sense reduced its self-sealing 35 capacity.

In connection with the filler needle portion 19 there is provided a closure pin 21' having a finger-hold or eye 22 at one end and being preferably of a diameter to frictionally fit the bore 45 of said portion 19 to protect the content of the filler 20 when not in use; while a suitable container 23 having a self-sealing cap 24 may also be provided for storage of the filler when not required and thus further preserving its content and utility.

In order to further increase the utility of the improved fountain pen of this invention, the closure or cap 14 is preferably provided with a plurality of longitudinally spaced holes 25, into any 50 55

pair of which are insertable the pins 26 rigidly carried by a conventional spring clip 27; said clip being clampingly engageable with variable tension to the cap 14 in the desired position by a ring 28, Figs. 1 and 6, having an outset 29 adapted to snugly open the clip between the pins 26, as well as of an interior diameter to similarly embrace the cap 14 in an obvious manner. Thus it will be readily apparent that by inserting the pins 26 in the selected holes 25 that the clip 27 can be locked in place at the requisite position for holding the pen in place in pockets of different depths, and with a variable tension controlled by said ring's position relative to the 10 clips active and, in an obvious manner, by movement towards or away from said action cord.

In some cases it may be found preferable that instead of the passage 12' being axially disposed relative to the feed-section 12 it may be longitudinally inclined relative to such axis as shown at 12" in Fig. 7, with equal advantages to those ascribed to the form shown by Figs. 1 and 5; while it is to be remarked corresponding references are applied to Fig. 7 in order to obviate 25 unnecessary repetitive matter.

From the foregoing description it is thought the use and advantages inhering to this invention will be clearly apparent; but it is deemed advisable to mention that said pen is forty per 30 cent lighter in weight than any known pen of corresponding size; that in view of its simplicity it can be thoroughly cleaned with a minimum of effort, and when the barrel is made of transparent material it is not only possible to see the 35 color of the contained writing fluid but also at a glance when refilling is necessary. Again by making the clip adjustable radial sweat holes are unnecessary; and withal by virtue of its novel

construction as a whole there is provided a pen of maximum ink carrying capacity and that is clean and sanitary at all times while being positively free of any tendency to leak even if laid on a flat surface for lengthy periods of time. 5

Obviously minor changes may be effected in structure details in adapting this invention to different types and styles of fountain pens without departing from the spirit and scope of the following claims. 10

Having thus described my invention, I claim:

1. A fountain pen comprising a barrel, a feed section carrying the writing instrumentality, said feed section having a longitudinal passage therethrough, a resilient material nipple closing in 15 the inner end of said feed section and adapted for penetration by a hollow-needle filler device.

2. A fountain pen comprising a writing fluid container barrel, a removable feed section carrying a conventional writing point, said feed section having an axial passage therethrough, and a resilient material nipple closing in the inner 20 end of said feed section, in combination with a filler device in the form of a compressible bulb having an attached tubular needle adapted for 25 free passage through the filler axial passage and "nipple."

3. A fountain pen as defined in claim 2 wherein in the inner end of the feed section is increased in diameter, and the "nipple" consists of a rubber closure of a length so that when fixed to the feed section it defines a hollow-hemispherical closure cap therefor. 30

4. A fountain pen as defined in claim 2 wherein in the filler needle portion outer end is tapered 35 to facilitate piercing of the feed closure hemispherical cap end.

WILLIAM G. NICHOL.
